Primary Examiner—T. Chase Nelson*Assistant Examiner*—Michael A Pratt(74) *Attorney, Agent, or Firm*—David O. Simmons(57) **CLAIM**

The ornamental design for a dual aperture gunsight body, substantially as shown and described.

DESCRIPTION

FIG. 1 is a perspective view of a first embodiment of a dual aperture gunsight body in accordance with the present invention;

FIG. 2 is a front view of the dual aperture gunsight body shown in FIG. 1;

FIG. 3 is a rear view of the dual aperture gunsight body shown in FIG. 1;

FIG. 4 is a right side view of the dual aperture gunsight body shown in FIG. 1;

FIG. 5 is a left side view of the dual aperture gunsight body shown in FIG. 1;

FIG. 6 is a top view of the dual aperture gunsight body shown in FIG. 1;

FIG. 7 is a bottom view of the dual aperture gunsight body shown in FIG. 1; and,

FIG. 8 is a perspective view of a second embodiment of a dual aperture gunsight body in accordance with the present invention, wherein the only difference being minor indentations within side surfaces (shown in FIGS. 4 and 5) that extend between front and rear surfaces (shown in FIGS. 2 and 3, respectively) and wherein it is understood that all other surfaces are the same as those of the first embodiment.
